DESIGN FOR A VENDING MACHINE CASING

Jean Rinaldi, New York, N. Y.

Application April 3, 1933. Serial No. 47,683

Term of patent 3½ years

To all whom it may concern:

Be it known that I, JEAN RINALDI, a citizen of the United States, residing at New York, in the county of New York and State of New York, have invented a new, original, and ornamental Design for a Vending Machine Casing, of which the following is a specification, reference being had to the accompanying drawing, forming part thereof.

I claim:

The ornamental design for a vending machine casing, as shown.

JEAN RINALDI.
